CAN CLOSING MACHINE

Robert M. Weygant and John S. Massey, Waukegan, Ill., assignors to American Can Company, New York, N. Y., a corporation of New Jersey

Application March 1, 1946, Serial No. 651,119

7 Claims. (Cl. 226—80)

1

The present invention relates to can closing machines and the like and has particular reference to an improved topping mechanism for use in such machines.

An object of the invention is the provision of an improved topping mechanism wherein the topping head is maintained in a substantially upright position by a double chain differential device which is of simple construction and one which provides accurate efficient operation.

Another object is the provision of such an improved topping mechanism for a can closing machine wherein a topping head is arranged for travel along a slightly inclined, straight line path of travel above the line of travel of a can to be topped, so that the topping head will enter the can gently and gradually to effect the topping operation without any splashing of the liquid contents of the can.

Numerous other objects and advantages of the invention will be apparent as it is better understood from the following description, which, taken in connection with the accompanying drawings, discloses a preferred embodiment thereof.

Referring to the drawings:

Figure 1 is a front elevation of a topping mechanism embodying the instant invention, with parts broken away;

Fig. 2 is a top plan sectional view of the mechanism taken substantially along the line 2—2 in Fig. 1, with parts broken away;

Fig. 3 is a transverse sectional view taken substantially along the line 3—3 in Fig. 1, with parts broken away;

Fig. 4 is a back elevation of the mechanism, with parts broken away; and

Figs. 5, 6 and 7 are enlarged fragmentary details of chains used in the mechanism.

As a preferred embodiment of the instant invention the drawings disclose a continuous operation topping mechanism for pushing solid matter in filled cans down below the top edge of the cans preparatory to the cans being closed and sealed with suitable covers. The mechanism may form a part of a more elaborate machine such as a closing machine for sealing the covers in place on the topped cans.

In such a closing machine filled cans A (Fig. 1) to be topped are advanced in spaced order and in a continuous procession along a table 11 which may be formed as a part of a frame 12 which constitutes the main frame of the can closing machine. Advancement of the cans is effected by a continuously moving endless feed chain 14 having feed dogs 15 secured thereto at spaced intervals along the chain. The chain may be driven in any suitable manner as by spaced sprockets forming a part of the can feed-in device of the closing machine.

2

The topping of the cans A is performed by a plurality of topping heads 17 which move along a straight line path of travel above the cans as they advance along the table 11. In the mechanism shown in the drawings, there are six of the topping heads 17. These heads are carried on an endless chain conveyor or topping chain 19 at spaced intervals each space being equal to the distance between the cans A moving along the table. For this purpose each topping head 17 is provided with an upright stem 20 (see also Fig. 3) which fits into a socket 21 formed in the head. A pin 22 holds the stem in place.

Each topping head stem 20 is secured to the outer overhanging end of a support shaft 25 (Figs. 1 and 3). There are six of these support shafts, one for each head. Each shaft is carried in a pair of spaced bearings 26 formed on special chain links 27 (Figs. 6 and 7) constituting parts of the topping chain 19. Between the bearings 26, each support shaft carries a support roller 28.

The topping chain 19 which carries the topping heads 17 operates over a pair of spaced sprockets 31, 32 (Figs. 1, 2 and 3) which are located one each adjacent the ends of the topping mechanism. These sprockets are provided each with a pair of clearance recesses 34 formed in their peripheries in diametrically disposed relation and provide clearance for the chain support rollers 28.

The topping chain sprocket 32 is an idler sprocket and is mounted on an idler shaft 36 (Fig. 2) journaled in a pair of spaced bearings 37, 38. Bearing 37 is formed in a back wall 39 of an open faced housing 40 having a depending integral bracket 41 (see Fig. 4) bolted to the frame 12 of the closing machine. The bearing 38 is formed on a right angle web 42 which extends out from the inner face of the housing back wall 39.

The topping chain sprocket 31 is a driving sprocket and is mounted on a drive shaft 45 journaled in a pair of spaced bearings 46, 47. Bearing 46 is formed in a cover plate 48 bolted to the back wall 39 of the housing 40 while bearing 47 is formed in a right angle web 49 which extends out from the inner face of the housing back wall.

The driving shaft 45 is continuously rotated in time with the passage of the cans A along the table. This is brought about by a gear 52 (Figs. 2, 3 and 4) which is mounted on the driving shaft. This gear meshes with and is driven by a gear 53 mounted on a jack shaft 54 journaled in a pair of spaced bearings 55, 56 formed in the cover plate 48 and in the housing 40 respectively. The jack shaft 54 is continuously rotated by a sprocket 61 which is carried on the inner end of the shaft adjacent the bearing 56. The sprocket is driven by an endless chain 62

which operates over a driven sprocket 63 mounted on the outer end of a stub shaft 64 journaled in a bearing 65 formed in the machine frame 12. The inner end of the stub shaft carries a main driving sprocket 66 which meshes with the feed-in chain 14 which propels the filled cans A along the table 11 of the machine.

Hence through the sprocket connection and gear train just described the topping chain drive shaft 45 is rotated at a suitable speed which drives the topping chain 19 and the topping heads 17 connected thereto, at the same lineal speed as the can feed chains 14. Thus the topping heads move with the chain along a straight line path of travel along the lower run of the chain in time with the travel of the cans along the table 11. At the end of this straight line path of travel the topping heads ride up around the idler sprocket 32 and return along the upper run of the chain.

In order to properly effect the topping operation, the lower run of the topping chain 19 is disposed at a slight angle to the table 11, the chain sloping downwardly toward the table in the direction of travel of the cans along the table. For this purpose the chain driving shaft 45 is elevated slightly above the idler shaft 36. The topping heads 17 are located on the topping chain in positions that align with the tops of the cans as the inclined lower run of the chain moves along with the cans passing across the table.

Hence as a topping head 17 rides around the topping chain driving sprocket 31 it moves down toward an incoming filled can A propelled by the can feed chain 14 and comes into position directly above the open top of the can as best shown in Fig. 1. As the topping head and the can continue to move along at the same speed, the inclined lower run of the topping chain brings the topping head down into the top of the can to effect the topping operation.

This downward movement of the head into the can continues slowly and gently along the entire length of the straight line lower run of the chain and thus results in a complete topping of the can without excessive loss by splashing of the contents of the can. This feature is of great advantage where some of the contents of the can is of a liquid nature. At the end of this topping operation the topping head is withdrawn from the can top quickly and gently by its movement upwardly around the idler sprocket 32 as hereinbefore mentioned.

All of the topping heads 17 are maintained in a horizontal position at all times during their travel with the topping chain 19 along its topping and return runs and while passing around the sprockets 31, 32. This is brought about by a differential sprocket 71 (Figs. 2, 3 and 4) which is formed on the inner end of each of the support shafts 25. All six of these sprockets mesh with a double differential chain 72 disposed adjacent the topping chain 19 and following a path of travel paralleling that of the topping chain.

The differential chain 72 is in fact two chains located side by side and formed as one chain as best shown in Fig. 5. Such a construction of chain produces a single wide chain having two parallel sprocket runs. The differential sprockets 71 operate with the innermost run of this chain. The outer run of the chain operates over an idler sprocket 73 and a driving sprocket 74. The idler sprocket is freely mounted on the idler shaft 36. The driving sprocket 74 is bolted to the inner face of a differential gear 75 freely mounted on the drive shaft 45. This gear meshes with 75 travel of the can, a topping head carried on said

and is driven by a gear 76 keyed to the jack shaft 54.

Through this gear train 75, 76 the differential chain 72 is operated at a lineal speed of travel which along its lower and upper straight line paths of travel is equal to that of the topping chain. Hence as the topping chain 19 carries its topping heads 17 along the straight line paths of travel, the differential sprockets 71 are not rotated by the differential chain but merely remain stationary since both chains are traveling at the same lineal speed. Thus the stationary sprockets hold the topping heads attached to the support shafts 25 in a predetermined level or horizontal position.

However, the angular speed of the sprockets 73 and 74 is slightly less than the angular speed of the sprockets 31 and 32. Hence as the topping heads 17 travel around the topping sprockets 31, 32 the differential sprockets 71 in mesh with the differential chain rotate slightly in the proper direction. The result of this difference is to maintain the heads in their level or horizontal position even while passing around the sprockets. In this manner the heads are maintained in a common position during their travel around the entire path of travel of the topping chain.

Provision is made for backing up the topping stems against tilting under pressure of the topping operation on the heads 17 as they travel along the lower run of the topping chain. For this purpose the support rollers 28, as they travel along the lower run of the topping chain, engage against and ride along the lower edge of a track or upper guide rail 81 (Figs. 1 and 3). This rail extends the full length of the lower run of the topping chain 19. The rail adjacent its ends is secured to the right angle webs 42, 49.

The inner end of each support stem 25 adjacent the differential sprocket 71 carries a support roller 82. These rollers, as the stems 25 travel along the lower run of the topping chain, engage against and ride along the upper edge of an auxiliary support track or lower guide rail 83. This lower rail extends parallel with the upper rail for the full length of the lower run of the topping chain and is secured to an adjacent wall 84 of the housing 40.

Hence when the topping heads 17 move down into the tops of the cans A, the upward pressure on the heads brought about by the resistance of the contents of the cans, is resisted by the rollers 28, 82 riding against the tracks 81, 83. Thus these support tracks keep the stems 25 level and thereby maintain the heads in proper position for efficient topping of the cans.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

We claim:

1. In a can topping mechanism, the combination of feeding means for advancing a filled can along a straight line path of travel and through a topping operation, an endless chain disposed above the path of travel of said can, the lower run of said chain sloping downwardly toward the path of travel of the can while passing through the topping operation and in the direction of 70 travel of the can, a topping head carried on said

5

endless chain, leveling means for maintaining said head in substantially axial disposition relative to said can throughout the length of travel with said endless chain, and actuating means for operating said chain in time with the travel of the can to bring said topping head into topping engagement gradually and gently with the contents of said filled can so as to avoid excessive spilling of the contents of the can during the topping operation.

2. In a can topping mechanism, the combination of feeding means for advancing a filled can along a straight line path of travel, an endless topping chain disposed above and extending along the path of travel of said can, a topping head carried on said topping chain, actuating means for operating said topping chain in time with the travel of the can to bring said topping head into topping engagement with said can for the topping operation, and means for maintaining said topping head in a level position throughout its entire cycle of travel with the topping chain.

3. In a can topping mechanism, the combination of feeding means for advancing a filled can along a straight line path of travel, an endless topping chain disposed above and extending along the path of travel of said can, a topping head carried on said topping chain, actuating means for operating said topping chain in time with the travel of the can to bring said topping head into topping engagement with said can for the topping operation, a differential sprocket for said topping head, a double differential chain operable in time with said topping chain, and driving and supporting sprockets for said double chain, said double chain having a run for meshing engagement with said differential sprocket and a separate adjacent run for meshing engagement with the driving and supporting sprockets for maintaining said topping head in a level position throughout its entire cycle of travel with the topping chain.

4. In a can topping mechanism, the combination of feeding means for advancing filled cans along a straight line path of travel and in spaced relation, an endless topping chain disposed above and extending along the path of travel of said cans, a plurality of pairs of support bearings carried in spaced relation on said topping chain, a support shaft freely carried in each pair of said bearings, a topping head secured to the outer end of each of said support shafts, actuating means for operating said topping chain in time with the travel of the cans to bring said topping heads into topping engagement with said cans for the topping operation, a differential sprocket secured to the inner end of each of said support shafts, a double differential chain operable in time with said topping chain, and driving and supporting sprockets for said double chain, said double chain having a run for meshing engagement with said differential sprockets and a separate adjacent run for meshing engagement with the driving and supporting sprockets for maintaining said topping heads in a level position throughout their entire cycle of travel with the topping chain.

5. In a can topping mechanism, the combination of feeding means for advancing filled cans along a straight line path of travel and in spaced relation, an endless topping chain disposed above and extending along the path of travel of said cans, a plurality of topping heads carried in spaced relation on said topping chain, actuating

6

means for operating said topping chain in time with the travel of the cans to bring said topping heads into topping engagement with said cans for the topping operation, means for maintaining said topping heads in a level position throughout their entire cycle of travel with the topping chain, and devices adjacent the path of travel of said topping heads for supporting said heads against the pressure resistance of the contents of the cans during the topping operation.

6. In a can topping mechanism, the combination of feeding means for advancing filled cans along a straight line path of travel and in spaced relation, an endless topping chain disposed above and extending along the path of travel of said cans, a plurality of topping heads carried in spaced relation on said topping chain, actuating means for operating said topping chain in time with the travel of the cans to bring said topping heads into topping engagement with said cans for the topping operation, means for maintaining said topping heads in a level position throughout their entire cycle of travel with the topping chain, and support tracks adjacent the path of travel of said topping heads for supporting said heads against the pressure resistance of the contents of the cans during the topping operation.

7. In a can topping mechanism, the combination of feeding means for advancing filled cans along a straight line path of travel and in spaced relation, an endless topping chain disposed above and extending along the path of travel of said cans, a plurality of support bearings carried in spaced relation on said topping chain, a support shaft freely carried in each of said bearings, a topping head secured to the outer end of each of said support shafts, actuating means for operating said topping chain in time with the travel of the cans to bring said topping heads into topping engagement with said cans for the topping operation, a differential sprocket secured to the inner end of each of said support shafts, a double differential chain operable in time with said topping chain, a driving sprocket and a supporting sprocket for said double chain, said double chain having a run for meshing engagement with said differential sprocket and a separate adjacent run for meshing engagement with said driving and supporting sprockets for maintaining said topping heads in a level position throughout their entire cycle of travel with the topping chain, a pair of support rollers mounted on said support shafts in spaced relation, and a pair of support tracks disposed in spaced relation adjacent the lower run of said topping chain, each track being engageable by one of said rollers on each shaft and located above and below the path of travel of the rollers for supporting said shafts against tilting under the pressure resistance of the contents of the cans during the topping operation.
